[57] ABSTRACT

A concrete pump having two counter operating pistons which operate under pressure and vacuum and a sliding valve plate which alternately covers the input to the pump and a blocking valve plate which alternately closes one or another passageway at the output of the pump so that concrete and other bulky materials can be forced by the pressure of one of the pistons from the input to the output of the pump in a smooth continuous flow.

FIG.1

FIG.2

FIG.3

FIG.4

FIG.5

CONCRETE PUMP

This invention relates to a concrete pump consisting of two counter vacuum or counter pressure piston means respectively, whereby the working cylinder is alternately connected with a common vacuum side, and with one of the passageways leading to the pressure line.

In a known embodiment, a separating wall extends through the vacuum suction passageway between the connecting pieces of a pipe for the pressure line so that an annular slide travels in a sealing movement on the upper front face of the vacuum passageway. The annular slide is vertically mounted on a blocking plate which is pivotally driven at the end of a switching shaft. While the annular slide interrupts the supply of concrete at one side of the separating wall and opens the other side, the blocking plate works counterclockwise thereto. This is achieved so that in the end position of the blocking plate, the annular slide alternately opens and interrupts the supply of concrete. In this manner, the working cylinders of two counter running vacuum and pressure piston devices whereby one is connected with a common vacuum side and with one of the passageways leading to the pressure line. Such an alternate switching arrangement has a number of disadvantages. The annular slide which moves on the upper front face of the separating wall is subject to a high degree of wear. The separating wall which separates the concrete supply passageway creates dead space. It is also difficult to sufficiently seal the annular seal around its edges.

Accordingly, the present invention overcomes the above mentioned disadvantages in providing a sliding plate which extends over the common vacuum side, and a blocking plate which laterally and alternately closes the passageways to the pressure line. Both are mounted on a switching or actuating shaft which runs parallel to the piston means.

It is therefore an object according to the present invention to provide a concrete pump which includes pressure and vacuum pistons which operate alternately in conjunction with a sliding valve plate to force concrete fed into the input of the pump out of a common output under high pressure.

It is another object according to the present invention to provide a concrete pump which is simple in design, reliable in operation and inexpensive in cost.

Other objects and features of the present invention will become apparent from the following detailed description considered in connection with the accompanying drawing which discloses the embodiments of the invention. It is to be understood however that the drawing is designed for the purpose of illustration only and not as a definition of the limits of the invention.

In the drawing wherein similar reference characters denote similar elements throughout the several views:

FIG. 1 is a longitudinal cross-sectional view through an alternating switching arrangement according to the invention;

FIG. 2 is a plan view of the device according to FIG. 1;

FIG. 3 is a cross-sectional view taken along line A-B of FIG. 2;

FIG. 4 is a cross sectional view taken along line C-D of FIG. 2; and

FIG. 5 is a cross sectional view taken along line E-F of FIG. 2.

Referring to FIGS. 1-5, the concrete pump of the invention essentially consists of two counter moving vacuum or pressure piston means respectively, whereby the associated working cylinders 1 and 2 are alternately connected with a common vacuum inlet side 3, and with passageways 5 and 6 leading to a pressure line 4. Passageways 5 and 6 are located at the end of a pipe 7. In the invention, a sliding or pivotal plate 8 extends over the two working cylinders 1 and 2, and the common inlet side 3. Pivotal plate 8 is mounted on a switching shaft 9 running parallel to piston means 1 and 2. Furthermore, at the end of switching shaft 9 is mounted a blocking plate 10 which alternately opens and closes passageways 5 or 6 respectively.

In the position shown in FIGS. 2 and 3, sliding plate 8 closes the concrete supply passageway 3 to the working cylinder 1, and opens the passageway to working cylinder 2. The concrete supply passageway to pressure line 4 is opened through passageway 5 by blocking plate 10 while passageway 6 is blocked. Therefore, a suction or vacuum stroke is carried out by working cylinder 2, and a pressure stroke is performed by working cylinder 1. After shaft 9 is switched, sliding plate 8 closes concrete supply passageway 3 and working cylinder 2, and blocking plate 10 closes passageway 5 in pressure line 4. In this manner, the vacuum or pressure piston means and their associated working cylinders 1 and 2 respectively, are alternately connected with a common suction side or opening 3 and with one of the open passageways 5 or 6 which are open with respect to pressure line 4. It is advantageous that blocking plate 10, which is vertically mounted on sliding plate 8, be pear shaped as shown in FIG. 3. Blocking plate 10 extends from the upper outer edge of sliding plate 8 to cover one of passageways 5 or 6 respectively. In this way the plate forms the connecting wall of the concrete supply passageway 3 opposite pressure line 4. The flange end of pipe 7 with associated passageways 5 and 6 serves as a closure for switching stations 3 to 10, and as a pivot bearing for switching shaft 9. As can be seen in FIG. 4 a rib 12 extends from the pivot bearing between passageways 5 and 6. Two ribs 13, corresponding to the pivot angle of sliding plate 8 also extend from the pivot between passageways 5 and 6.

It is another feature of the invention that switching shaft 9 be adjustable in axial direction on closure 11 for bringing the blocking plate 10 in sealing engagement with ribs 12 and 13. Therefore, a simple seal is formed and maintained between the suction or vacuum side, and the pressure side.

The invention also provides that an intermediary plate 15 be provided between housing 14 of switching plate 3 to 13. This intermediary plate 15 is provided with abutment 19 which limit the pivotal movement of sliding plate 8. The engagement of the sliding plate 8 with its upper outer edge onto abutments 19 at the end of an adjustment movement lessens the wear on the switching station. Moreover, all parts can be easily assembled.

It is essential that closure 11 and intermediary plate 15 be mounted on housing 14 by screws 16 which are easily removable. This facilitates a removal of all individual parts in the switching station in the event they have to be replaced. In such a case, closure 11 together with pipe 7 is removed.

It is also a part of the invention that housing 14 be provided with two longitudinal bores 17 and 18 which at one end, connect to pipe 7 of pressure line 4 across passageways 5 and 6, and open to concrete supply inlet 3, while at opposite end are connected to working cylinders 1 and 2 of the piston means. In this way, a compact switching station is obtained using the least amount of space possible. 5

In a preferred embodiment, each of the pistons are coupled directly or indirectly to the drive shaft so that the sliding valve plate will close off the inlet of the passageway under compression while the locking plate will open its output to permit the concrete to flow into outlet member 7. 10

While only a single embodiment of the present invention has been shown and described it is obvious that other changes and modifications may be made thereto without departing from the spirit and scope of the invention. 15

What is claimed is:

- 20 1. A concrete pump comprising:
a hollow housing having at least two passageways formed therein, and an input opening communicative to each of said passageways;
a cylinder coupled to one end of each of said passageways;
a piston slidably disposed in each of said cylinders for compressive movement therein;
a drive shaft rotatably disposed in said housing and coupled to each of said pistons;
a funnel-shaped closure secured over the opposite end of said passageways defining the output of said housing, said closure having a pivot bearing for pivotably securing one end of said drive shaft;
a pear-shaped blocking plate pivotably disposed for 25 movement over the output member of said housing

for alternately closing at least one of said passageways, and opening at least one of said passageways communicative to a cylinder under compression;

and a sliding valve plate axially connected to said drive shaft for alternately opening and closing the input opening to each of said passageways, said sliding valve plate being connected to said blocking plate so as to cover and seal the input opening of a passageway under compression, said sliding valve plate being moveable over the entire width of the input opening of the passageways, wherein said funnel-shaped closure additionally includes a first rib extending between the output of said passageways and a second pair of ribs connected to said first rib and defining the pivot angle of said sliding valve plate.

2. The concrete pump as recited in claim 1 wherein said drive shaft is axially adjustable against said first and second ribs at the output of the passageways.

3. The concrete pump as recited in claim 1 additionally comprising an intermediate plate disposed between the funnel-shaped closure and the output of said passageways, and abutments provided on said intermediate plate for limiting the sliding movement of said sliding valve plate.

4. The concrete pump as recited in claim 3 further comprising screws threadably coupled to said housing for detachably mounting said funnel-shaped closure and intermediate plate to said housing. 30

5. The concrete pump as recited in claim 1 wherein said passageways comprise longitudinal bores formed within said housing and converging at the output of the housing.
